CLAIM

The ornamental design for a display screen or portion thereof with icon as shown and described.

DESCRIPTION

FIG. 1 is a front view of a display screen or portion thereof with icon according to the claimed design; and,

FIG. 2 is a front view of the display screen or portion thereof with icon showing the icon in a use environment.

The dash-dot broken lines in the figures showing the display screen or portion thereof illustrate portions of the display screen or portion thereof with icon that form no part of the claimed design. The dash-dot broken lines in FIG. 2 illustrating the environment of the icon form no part of the claimed design.

1 Claim, 1 Drawing Sheet
